DISPENSING DEVICE

José Pereira Lima, São Paulo, Brazil

Application June 29, 1935, Serial No. 29,147
In Brazil July 6, 1934

3 Claims. (Cl. 221—114)

This invention relates to improvements in floor-waxers or polishers comprising a rigid tube, formed of two readily assembled pieces, conveniently bent, and having on its upper end a container for liquid wax or varnish and a mechanism to supply the wax or varnish, when desired and in suitable quantities, to a removable felt placed at the lower end of the tube in a reinforced and removable piece provided with a removable device for distributing the liquid over the felt. This apparatus may or may not be provided with a handle for facilitating its use when waxing or polishing floors.

It will be seen from the above that this invention has the advantage of sparing its operator the necessity of dirtying his hands with wax or varnish inasmuch as either substance is poured in a liquid condition into the container before starting the work and this liquid is fed in desired quantities through the feeding mechanism, to the felt for application on the floor.

In describing the invention in detail, reference will be had to the accompanying drawing forming part of this application, wherein like characters denote corresponding parts in the several views, and in which—

Figure 1 illustrates a side elevation of the complete apparatus;

Figure 2 illustrates a longitudinal section of the upper part of the apparatus showing the container of the liquid substance for waxing or polishing and the mechanism to supply wax or varnish in suitable quantities;

Figure 3 is a longitudinal section through the lower part of the device; and

Figure 4 is a section on the line F—F of Figure 3.

Referring to the drawing, Figure 1 shows at A the two piece tube conveniently bent; B denotes the container; C the reinforced piece provided with the waxing or polishing felt D. For portability, tube A is formed of two pieces a and b for simple and easy assembling.

The container B (Figure 2) has a hermetic cover and a special internal device provided with valves permitting intermittent discharge of a certain amount of liquid wax or varnish. In the center of the cover there is a hole in which is fitted the piece 1 of valve 2, which also acts as a guide to button 3 fixed to the upper end of tube 4. By a slight pressure upon button 3 outside air is admitted into container B through a space between the said piece 1 and button 3. At the bottom of container B another hole is provided, 55 through which passes tube 5 which controls the

amount of liquid to be released. Valve 2, which may be made of metal or hard fibre and provided with a felt or leather washer, slides on tube 4 and is pressed against the piece 1 by means of a spring 6. Valves 7 and 8 are connected to one another by the tube 9, the valve 7 being connected to the button by a tube 4. The tubes 4 and 5 are provided with ports I, II and III affording communication between the container B and the lower part of the device. On the lower end of tube 5 is screwed piece 10 which serves as a guide for stem 11 and at the same time acts as a support for spring 12 which keeps valve 8 closed and, consequently, holds valve 7 open. On the upper part of tube 5 is also screwed piece 13, 15 which serves as a guide for tube 4 and as a support for spring 6 keeping valve 2 closed. Piece 13, in conjunction with sleeve 14, also holds to container B, the valve assembly and the support 15 of handle E, there being provided leather or fiber washers between these parts to avoid leakage and thus forming a compact assembly. This complete assembly is secured to the tube A by a sleeve 14 wherein is fitted the upper part of the tube 5.

As shown in Figure 3, the lower part C' is provided with a tubular extension C wherein is fitted the lower end of the tube A. From the body of the member C' the liquid flows to the distribution chamber 16 and thence, through screen 17, it spreads evenly over felt D which is fixed and pressed to the side walls of socket 18 by the movable piece 19 which hinges on an axis, fixed to one of the side walls of socket 18, and is fixed to the opposite wall by means of a bolt, thereby permitting quick and easy removal and replacement of the felt when a different colour of wax or varnish is to be used.

In order to make easier and handier the use of this apparatus, a handle E may be employed 40 which will enable the operator to stand up and handle the apparatus with one hand only without having to stoop to open the valve.

According to this invention, the operation of the apparatus will be as follows: The apparatus 45 is held with the left hand by handle E, resting felt D on the floor to be waxed or polished, and with the right hand the cover of the container B is held and given a slight rotation movement leftward and lifted thereby disconnecting 50 it completely from the apparatus; the container is then filled with the waxing or polishing liquid up to the level of vent I in tube 4; the cover is again placed over the container so that the bayonet slots 20 of the container engage the pins 55

21 of the cover and with a slight pressure and a slight rightward rotative movement the container is closed. Obviously, such hermetical sealing can also be achieved by any other suitable devices. When this is done, button 3 is pressed downward, then immediately relaxed, and, by holding the apparatus by handle E with the right hand, felt D is brushed over the floor to be waxed or polished.

10 When pressing button 3, which moves simultaneously the three valves, valve 2 opens admitting air into container B through the space between the button and the piece 1; at the same time valve 7 closes, thereby limiting the discharge to the quantity contained in the tube 5, and valve 8 opens releasing the liquid contained in tube 5. When button 3 is released, valves 2 and 8 close and valve 7 opens thereby filling up tube 5 again and in this way it is again ready to feed another supply of liquid.

The liquid from tube 5 is led through tube A to chamber 16 and thence to felt D after passing through screen 17, which distributes same evenly over felt D, which in turn distributes the liquid quickly and perfectly over the floor to be waxed or polished.

When the first supply of liquid is distributed and exhausted, button 3 should again be pressed and relaxed in order to again moisten felt D, and so on until the waxing or polishing of the floor is completed.

I claim:

1. In a floor waxer of the type having a tubular handle provided with a reservoir at its upper end and a spreading head at its lower end, means for controlling the flow of fluid from said reservoir to the upper end of said handle including an outer tubular member extending downwardly through the bottom of said reservoir into said handle, an inner tubular member concentrically spaced within the outer tubular member and extending therethrough, said inner member being longer than the outer member and having lateral ports adjacent its upper and lower ends, a pair of valves carried by said inner tubular member at the upper and lower ends thereof and seating respectively on the corresponding ends of the outer tubular member, spring means urging the inner tubular member into raised position to seat the lower valve, and manually operative means for moving the inner tubular member downwardly to unseat the lower valve and seat the upper valve.

2. In a floor waxer of the type having a tubu-

lar handle provided with a reservoir at its upper end and a spreading head at its lower end, means for controlling the flow of fluid from said reservoir to the upper end of said handle including an outer tubular member extending downwardly through the bottom of said reservoir into said handle, an inner tubular member concentrically spaced within the outer tubular member and extending therethrough, said inner member being longer than the outer member and having lateral ports adjacent its upper and lower ends, a pair of valves carried by said inner tubular member at the upper and lower ends thereof and seating respectively on the corresponding ends of the outer tubular member, spring means urging the inner tubular member into raised position to seat the lower valve, a vent tube extending upwardly from and fixed to the inner tubular member, said vent tube having vent openings adjacent its upper end, and a button on the upper end of the vent tube projecting through the top of said reservoir to depress the vent tube as the button is depressed.

3. In a floor waxer of the type having a tubular handle provided with a reservoir at its upper end and a spreading head at its lower end, means for controlling the flow of fluid from said reservoir to the upper end of said handle including an outer tubular member extending downwardly through the bottom of said reservoir into said handle, an inner tubular member concentrically spaced within the outer tubular member and extending therethrough, said inner member being longer than the outer member and having lateral ports adjacent its upper and lower ends, a pair of valves carried by said inner tubular member at the upper and lower ends thereof and seating respectively on the corresponding ends of the outer tubular member, spring means urging the inner tubular member into raised position to seat the lower valve, a vent tube extending upwardly from and fixed to the inner tubular member, said vent tube having vent openings adjacent its upper end, a button on the upper end of the vent tube projecting through the top of said reservoir to depress the vent tube as the button is depressed, a valve seat carried by the top of said reservoir in annular spaced relation to said button, a valve flange carried by the button and normally closing upwardly onto said valve seat, and other spring means urging said button into upward position independent of the vent tube.

JOSÉ PEREIRA LIMA.
